UNITED STATES PATENT OFFICE.

HENRY L. TIFFANY, OF SOUTH DARTMOUTH, MASSACHUSETTS.

CONE-TUBE.

1,175,201.

Specification of Letters Patent. Patented Mar. 14, 1916.

Application filed March 25, 1915. Serial No. 17,036.

To all whom it may concern:

Be it known that I, HENRY L. TIFFANY, a citizen of the United States, and a resident of South Dartmouth, in the county of 5 Bristol and State of Massachusetts, have invented an Improvement in Cone-Tubes, of which the following description, in connection with the accompanying drawings, is a specification, like characters on the drawings representing like parts.

This invention relates to cone tubes adapted to receive or have wound thereon yarn, thread or the like of the commonly known cone winding form and from which the 15 yarn is drawn off axially or substantially so.

In certain aspects thereof, my invention is an improvement upon that shown in the patent to Charles Gess, No. 986,379, dated March 7, 1911.

20 In order that the principle of the invention may be readily understood, I have disclosed a single embodiment thereof in the accompanying drawing, wherein—

Figure 1 is a side elevation of a cone tube 25 embodying my invention; Fig. 2 is a vertical, central section thereof; Fig. 3 is a plan view of the tube shown in Fig. 1; Fig. 4 is a cross sectional view thereof; Fig. 5 is a sectional view of the tip end of the tube; 30 Fig. 6 is a plan view of the blank from which the cone tube is wound; Fig. 7 is a side elevation of the upper portion of a cone tube constituting a modified form of my invention; and Fig. 8 is a vertical, central section taken through the cone tube 35 shown in Fig. 7.

Cone tubes adapted to receive or have 40 yarn or thread wound thereon and from which said yarn or thread is drawn off axially when in upright position are customarily formed of paper rolled in one or more layers or coils into conical form. These tubes are adapted to be mounted for winding upon tapering arbors of the general shape of the 45 tubes and extending through said tube to within an inch or two of the tip end thereof. The ends of these conical tubes generally protrude somewhat from the complete yarn or thread mass. A cone tube of this general 50 character but having an inturned apex end is disclosed in said Gess Patent No. 986,379, and I have represented the disclosed embodiment of my invention as applied thereto.

Referring more particularly to the draw-

ings and to the single embodiment of the invention here illustrated, the blank from which the cone or tube is formed is represented at 1 in Fig. 6, it being preferably of the segmental shape there shown. The said blank is coiled as indicated in Fig. 4 into a 55 suitable number of contacting layers and the inner edges of the said layers should for the best results terminate substantially flush with each other, as indicated at 2 in Fig. 5.

Owing to the fact that the conical tubes 60 are markedly tapering to facilitate the unwinding of the yarn or thread (such tapering materially exceeding that of the usual spinning spindle), it is exceedingly important in effecting the best results that such 65 cone tubes be superficially roughened, thus preventing the slipping or displacement of the yarn or thread as the first series of 70 layers thereof are wound upon the tube and subsequently. This tendency to displacement, particularly of the first laid layers, 75 exists to a marked degree in a cone having a decided taper, but it is nevertheless of importance that the cone tube and the yarn package wound thereon be of decided or 80 markedly tapering form. Such roughening may be of any suitable character, though preferably it is effected by providing the cone tube with longitudinal ridges 3 inclined from top to bottom, such roughening being effected either prior or subsequently to 85 the coiling of the paper or other material into tube form, but preferably while the material is in its flat form. If as prepared the cone tube be superficially roughened, the 90 roughened portion is removed from the tip portion of the tube which, as stated, should present no obstruction to the unwinding of the yarn or thread and especially to the unwinding of the first laid layers thereof. 95

In order to prevent the first laid coils or 100 layers of the yarn or thread from contacting with the tip end of the cone tube as they are unwound therefrom, the tip end 5 thereof is inturned or upset in any suitable manner, as represented most clearly in Figs. 1, 2 and 5. The tip end of the cone tube should, for effecting the best results, be very materially inturned and preferably so as substantially, if not wholly, to close said tip end, and the 105 inturned end may be turned into the cone tube to any desired extent so as to provide a downwardly extending edge portion.

The tip end of the cone tube, as yarn or thread is being wound thereon, projects very materially beyond the tapered end of the supporting arbor. The approximate position of the outer end of the arbor is indicated by the dotted line $x-x$ in Fig. 2, and is therefore free from contact with the said tip end of the cone tube. It is therefore possible to upset or inturn the tip end of the cone to a very marked degree and so as effectively to prevent the breaking or chafing of the yarn or thread by said tip end as the yarn or thread is unwound.

The cone is markedly conical in order to permit the yarn to free itself from the roughened surface when drawn from the end of the cone and is provided with stiff, cone supporting, side walls to sustain the usually large and heavy package. The tip end of the cone preferably is not only inturned but is smooth, the roughened surface of the body of the cone blending into the smooth, inturned surface of the tip. The said inturned tip end is preferably indifferently centered internally with respect to the axis of the cone, this being possible because the tip end of the cone extends beyond the driver. This is a matter of practical importance, inasmuch as if, in manufacturing the cone, the apex end thereof be somewhat warped or distorted, the fact that the tip end extends beyond the driver permits it to conform in position substantially to the driver, whereby the yarn or thread as drawn off will not be obstructed or impaired by said warped or deflected portion.

In effecting the inturning of the tip end of the cone tube, the material of such tip may be somewhat twisted or circumferentially displaced, as indicated at 6 in Figs. 1 and 3.

When the cone tube is in its normal condition,—that is, before the tip end thereof has been inturned,—such tip end is substantially unyielding to inward pressure. When, however, the material of the tube has been circumferentially displaced, then the arch effect existing prior to inturning is materially lost and the twisted portions of the edge, because of their displacement, will more readily yield inwardly. This inturning may be satisfactorily effected by subjecting the unturned end to the action of a die, the die and cone tube having a movement of relative rotation. Such relative rotation of the cone tube and die coincidentally softens the material of the tip end portion, thus enabling it to be turned inwardly and to lie snugly in the die and to receive the smooth, highly desirable, polished surface. Such softening of the tip end renders such tip end less stiff and lacking in rigidity than the body of the tube, it being therefore more pliable and yielding than the body thereof.

65 This, however, renders the tip end liable to

be crushed or damaged in transportation. In order to overcome the effect of such softening action and to reinforce the tip end of the tube, and in certain cases so as merely or substantially to neutralize the softening due to the inturning action, I provide a reinforcing element or device which in the preferred embodiment of the invention is represented in Figs. 2 and 5 as a cap 7 of thin sheet steel, which is adapted to be inserted within the tip portion of the tube prior to the inturning action. Such cap may be of any suitable thickness and of any suitable degree of stiffness or rigidity, so as if desired merely to neutralize the described softening due to the inturning action, or if desired, so as to strengthen the cone tube more materially at this point and thus rendering it of materially greater strength at the inturned tip end than throughout the body.

The cap 7 may be applied in any suitable manner and preferably through the larger end of the cone tube, though the material of the cone may be rolled thereabout. Preferably the cap is provided at its lower edge with a series of teeth or projections 8 which may be slightly out-turned so as readily to penetrate into the inner wall of the cone tube as represented in Figs. 2 and 5. After the insertion of the cap 7, if it be so applied, the end of the cone tube is upset or inturned in any suitable manner, as by subjecting it to the action of a die, which has a movement of relative rotation with respect to the cone tube.

While I preferably provide a unitary cap piece, I may reinforce the tip end by a series of more or less distinct parts which converge from their lower ends to the central portion of the inturned tip end.

Within the scope of my invention, the reinforcing member or cap piece may be applied to the outer surface of the cone tube. Such form of my invention is illustrated in Figs. 7 and 8, wherein is shown a cap piece 9 having at its lower edge teeth 10 adapted to penetrate the outer surface of the cone tube. Such cap piece is preferably applied subsequent to the inturning of the tip end, though within the scope of my invention, it may be applied at any suitable time, as, for example, simultaneously or substantially simultaneously with the inturning action. In order to prevent chafing or breaking of the yarn or thread in the unwinding action, the outer wall of the body of the cone tube should merge without interruption and smoothly into the lower edge of the cap 9. Preferably also the outer surface at least of the cap 9 is highly polished so that it presents no obstruction to the unwinding of the yarn or thread. The cap piece shown in both forms of the invention is preferably provided with an axial open-

ing 11 coinciding with the axial opening which may be left in the tip end of the cone tube.

A cone tube constructed in accordance with my invention may readily be transported without liability of damage to the tip end, even though such cone tubes have heavy packages of yarn wound thereon and from which said tip ends protrude.

Having thus described one illustrative embodiment of my invention, I desire it to be understood that although specific terms are employed, they are used in a generic and descriptive sense and not for purposes of limitation, the scope of the invention being set forth in the following claims.

Claims:

1. As an article of manufacture, a winding cone having a yarn-retaining surface markedly conical in shape, the wall of the cone being inturned at the tip end and provided with a reinforcing device to maintain its contour.

2. As an article of manufacture, a winding cone having a yarn-retaining surface markedly conical in shape, the wall of the cone being inturned at the tip end and provided with a reinforcing cap to maintain its contour.

3. As an article of manufacture, a winding cone having a yarn-retaining surface markedly conical in shape, the tip end of the cone being inturned and provided with

a reinforcing cap having cone wall penetrating teeth.

4. As an article of manufacture, a winding cone having a yarn-retaining surface markedly conical in shape, the tip end of the cone being inturned and provided internally with a reinforcing cap.

5. As an article of manufacture, a winding cone having a yarn-retaining surface markedly conical in shape, the tip end of the cone having an applied, reinforcing device of a strength substantially to neutralize the softening caused by the inturned action of the tip end.

6. As an article of manufacture, a winding cone having a yarn-retaining surface markedly conical in shape, the tip end of the cone being inturned and provided with a thin, metallic cap secured to a surface thereof.

7. As an article of manufacture, a winding cone having a yarn retaining surface markedly conical in shape and a soft surfaced rounded end, which end is stiffened by an internal reinforcement.

In testimony whereof, I have signed my name to this specification, in the presence of two subscribing witnesses.

HENRY L. TIFFANY.
